UNITED STATES PATENT OFFICE.

ESMERALDA CROCKER, OF NEW YORK, N. Y., ADMINISTRATRIX OF JOHN CROCKER, DECEASED, ASSIGNOR TO FREDERICK LEACH, OF SAME PLACE.

BOX.

SPECIFICATION forming part of Letters Patent No. 544,462, dated August 13, 1895.

Application filed April 2, 1895. Serial No. 544,158. (No model.)

To all whom it may concern:

Be it known that JOHN CROCKER, a citizen of the United States, and a resident of New York, in the county of New York and State 5 of New York, did invent certain new and useful Improvements in Boxes, of which the following is a specification.

This invention, while applicable to boxes generally that are provided with covers which 10 have a depending flange that shuts down and around the upper edge of the box when applied thereto, has reference more particularly to that class of such boxes which are intended for containing and holding small articles— 15 such, for instance, as sewing-machine needles, screws, the parts of watches, and the like. In the construction of boxes of this class as heretofore in use the box and cover have been so formed that the walls of the former have been 20 made of a uniform height throughout, and the cover when applied thereto was supported by such walls entirely around the box, with no provision made for allowing of its easy removal. As a result of this, the removal of the 25 cover, when required, could only be effected by holding the box in one hand and raising or drawing the lid therefrom with the other. This operation, when the boxes are large and the depending flanges on the cover are not deep 30 or wide, is in most cases readily accomplished, but when the boxes are small and shallow and the depending flange on the cover closes down over a considerable portion of its walls the portion thereof which is exposed and may 35 be grasped by the hand is so reduced in size that it is extremely difficult to hold the same while the removal of such cover is being effected, especially if it is closely fitted to the box, as it usually is, and as a consequence 40 thereof the contents of the box is dumped or spilled when such removal takes place, which is a result that may entail great loss, especially when such contents consists of jewels or other expensive articles. The object of 45 the invention is to obviate this difficulty and to provide a box of the class mentioned in which the removal of the cover may be effected by merely pressing downward upon one end thereof and thereby tilting the same, after 50 which the cover may be raised from the box without the dangers above explained.

To this end the invention consists of a box having a fulcrum arranged upon the upper edge of its walls and a cover for co-operating therewith having a depending flange for embracing and sliding down over this portion of the walls, all as will hereinafter more fully appear.

Referring to the accompanying drawings, which form a part of this specification, Figure 1 is an isometrical projection of a box constructed in accordance with the said invention having the cover applied thereto; Fig. 2, a side elevation of a box and cover of similar construction, illustrating the manner 65 of tilting the cover when it is desired to remove the same from the box, the cover being shown in longitudinal section; Fig. 3, a similar view of a slightly-modified construction of box in which the cover may be tilted toward either end thereof, the cover in this figure being shown in dotted lines; and Fig. 4, a longitudinal sectional view of a box of a still further modified construction.

In all the figures like letters of reference are 75 employed to designate corresponding parts.

A indicates a box, which is provided with the usual bottom *a* and side walls *a'*, and B a cover having the depending flange *b*, which is adapted to shut down over and around the 80 side walls *a'* when applied to the box, all as is shown. This box and cover may be made of any preferred material, and, as thus far described, they are or may be of the ordinary and usual constructions. The side walls *a'*, however, instead of being made with an upper edge that rests against and supports the cover throughout the entire extent of such edge, as heretofore, are provided with a fulcrum thereon, over which the cover may be tilted when 85 it is desired to remove it from the box by simply depressing the same at one of its ends, as shown more clearly in Figs. 2 and 3. This fulcrum may be constructed in various ways. In Figs. 2 and 3 it is shown as formed by cutting away in a downwardly and outwardly direction the upper edge of the side walls *a'*, leaving an angle or corner *a*² thereon, which constitutes the fulcrum, while in Fig. 4 it is shown as formed from abutments secured to 90 the interior of the cover and resting upon the upper edge of the side walls *a'*. When this

last form of construction is employed, the abutment or fulcrum may be made either in the form of a wire a^3 , extending across the interior of the cover from side to side, or 5 pieces of metal a^4 of the required shape may be secured in such cover in proper relation to the side walls a' as to rest thereon when the cover is applied to the box.

The fulcrum being constructed in either of 10 the ways above specified may be located at one end only of the box, as shown in Fig. 2, or a separate fulcrum may be located at each end thereof, as illustrated in Figs. 3 and 4. Either of these arrangements may be adopted 15 as may be preferred, it being understood, however, that when but a single fulcrum is employed the tilting of the cover can be effected in only one direction, but when a separate fulcrum is employed at each end thereof the 20 tilting may be accomplished toward either end of the box as may be desired. As the box and cover are thus constructed, when it is desired to remove the latter from the former all that is required is to press upon the end of 25 the cover in rear of the fulcrum, when such cover will be tilted upward over the same, as shown in Figs. 2 and 3, and its removal then readily effected in the usual way.

Although in the foregoing the best means 30 contemplated have been described for carrying the invention into practice, it is to be distinctly understood that it is not limited strictly thereto, as it is obvious that the same may be modified in various ways without departing 35 from the spirit thereof—as, for instance, instead of making the abutments in the cover in the form of wires or pieces of material secured therein, if so desired such abutments

may be made by embossing them up in the material of the cover or side walls of the box. 40

Having now described the invention and specified certain of the ways in which it is or may be carried into effect, what is claimed is—

1. The combination, with a box, and a removable cover provided with a depending flange for closing down and around the side walls of such box, of a fulcrum, over and upon which the cover may be tilted when it is desired to remove it from the box, interposed between such cover and box, substantially as described. 45

2. The combination, with a box provided with a fulcrum on its upper edge, of a removable cover having a depending flange for closing down and around the side walls of such box, and capable of being tilted over such fulcrum when it is desired to remove it from the box, substantially as described. 50

3. The combination, with a box provided with a fulcrum, a^2 , formed on the upper edge of its side walls, of a removable cover provided with a depending flange extending down around the side walls of such box, and resting upon such fulcrum, whereby to be capable of being tilted thereover when it is desired to remove the cover from the box, substantially as described. 55

In testimony whereof I have hereunto set my hand this 29th day of March, 1895.

ESMERALDA CROCKER,
*Administratrix of the estate of John Crocker,
deceased.*
